(57) **CLAIM**

The ornamental design for a display screen with graphical user interface, substantially as shown and described.

DESCRIPTION

FIG. 1 is a first embodiment of a display screen with graphical user interface; and,

FIG. 2 is an enlarged view of the encircled portion labeled as '2' in FIG. 1, shown separately for completeness of illustration.

The even broken lines, dash-dot lines, and text shown in broken lines in the drawings illustrate portions of a display screen with graphical user interface that form no part of the claimed design.
